DESIGN FOR A KEY CASE

George Landberg, Bronx, N. Y.

Application May 10, 1940, Serial No. 92,257

Term of patent 7 years

To all whom it may concern:

Be it known that I, George Landberg, a citizen of the United States and resident of the Bronx, New York, in the county of Bronx and State of New York, have invented a new, original, and ornamental Design for a Key Case, of which the following is a specification, reference being had to the accompanying drawing, forming a part thereof, and of which Figure 1 is a view in front elevation in closed position of a key case showing my new design, Fig. 2 is a similar view of the opposite side thereof, Fig. 3 is a view in edge elevation of the key case shown in Fig. 1, and Fig. 4 is a view in front elevation showing the case in open position.

I claim:

The ornamental design for a key case, substantially as shown.

GEORGE LANDBERG.
